FLATIRON-CORD SUPPORT

Clarence L. Mulder, Grand Rapids, Mich.

Application September 16, 1940, Serial No. 357,053

3 Claims. (Cl. 248—51)

This invention relates to a flatiron stand and cord support and has for an object to provide a device of this character in which the flatiron stand is provided with flanges at the front and rear thereof adapted to positively prevent dislodgement of the flatiron from the stand should the ironing board be tipped.

A further object is to provide a flat iron stand provided with a channel member for securing a flexible cord holding rod in upright position to the stand, the rod being rotatably mounted so as to be extended horizontally along the ironing board when not in use and latched in released position.

A further object is to provide apparatus of this character which will be formed of a few strong, simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming a part of this specification:

Figure 1 is an end elevation of a flatiron stand and cord support constructed in accordance with the invention and applied to an ironing board.

Figure 2 is a plan view of the parts shown in Figure 1.

Figure 3 is a perspective view of the cord holding rod and support therefor.

Figure 4 is a side elevation of the cord holding rod and support with the rod latched in released position.

Figure 5 is a perspective view of the bracket which secures the flatiron stand and cord holding rod and support to the ironing board.

Referring now to the drawing in which like characters of reference designate similar parts in the various views, the flatiron stand is shown to comprise a substantially rectangular metal plate 10 having a rounded end 11 and provided at the corners with upwardly and inwardly inclined flanges 12, spaced opposite each other and adapted to permit application of and lifting off the flatiron 13 from the plate when it is disposed along the longitudinal center line of the plate with its pointed end 14 disposed upon the rounded end 11 of the stand. When the flatiron is applied to the stand, it is slid rearwardly so

that one side of the pointed end of the flatiron engages one of the front flanges 12 while the rear end of the flatiron engages both the rear flanges 12. In this position the flat iron is disposed obliquely to the longitudinal center arm of the stand as shown in Figure 2 and due to the slope of the flanges the flanges overlap the flatiron and prevent dislodgement of the flatiron from the stand should the ironing board 15 be tipped.

For mounting the flatiron stand upon the ironing board an angle bracket 16 is provided, the same having a horizontal long top leg 17 and a short upright leg 18. The upright leg is provided with a laterally extending foot 19 provided with openings 20 to interchangeably receive a bolt 21 which may be engaged through the ironing board. A wing nut 22 is threadedly engaged with the nut and is adapted to be screwed tight against the foot 19 to hold the bracket either longitudinally of the ironing board and spaced thereabove or swung to one side of the ironing board as desired.

A sheet 23 of asbestos is interposed between the long leg 17 of the securing bracket and the bottom of the flatiron stand 10. A washer 24 is interposed between the foot 19 of the supporting bracket 16 and the ironing board to permit being moved to operative positions freely on the ironing board.

The flat iron stand 10 may be pivotally mounted or mounted stationary on the long leg 17 of the supporting bracket and for this purpose the long leg is provided with a plurality of openings 25, two of which may be used to receive securing bolts, not shown, when desired to mount the stand stationary and one of which may be used to loosely receive a securing bolt 26, shown best in Figure 2, to pivotally mount the stand on the bracket. A channel metal support 27 is secured to the long leg 17 of the securing bracket by a pivot bolt 28, shown best in Figure 4, passed through an opening 29 in the long leg of the bracket. A cord holding rod 30, preferably formed of resilient wire, is provided at its lower end with a horizontal shaft 31 which is passed through openings 32 formed in the flanges of the channel support 27, one of the shaft being provided with an enlarged head 33, best shown in Figure 2, to prevent the shaft becoming dislodged from the channel support. The cord holding rod is provided at its upper end with a guide loop 34 to receive the cord 35 of the flatiron and is provided between its ends with

spring loops 36 and 37 through which the cord may be trained.

A helical spring 38 is provided with an eye 39 at the upper end which is engaged over the lower side of the lowest spring loop 36 as is best shown in Figure 3. The lower end of the cord is provided with an eye 40 which is secured in an opening 41 formed in one of the flanges of the channel support 27. The spring normally holds the cord rod 30 in upright position against a stop flange 42 which projects laterally from one of the flanges of the channel support 27. The upper eye 39 of the spring may be slid out of the loop 36 and down upon the cord rod 30 to permit the rod being swung to the horizontal or to released position to extend along the ironing board when not in use.

For latching the cord rod 30 in a released condition a substantially U-shaped latch 43 has one of its legs pivotally mounted in an opening 44 formed in one of the flanges of the U-shaped support. The other leg of the latch is adapted to be engaged in an opening 45 of said flange of the support above the cord rod so that the latch will hold the cord rod in released position when desired.

Since the operation of the parts has been described as the description thereof progressed, it is thought the invention will be fully understood without further explanation.

What is claimed is:

1. A flatiron cord support comprising, a bracket adapted to be secured to an ironing board and having a horizontal arm spaced upwardly from the ironing board, upwardly directed flanges on a portion of the horizontal arm, a cord guiding arm provided at its lower end with a horizontal shaft mounted in bearing openings formed in said flanges to permit the arm to be swung to the vertical and to the horizontal, a cord engaging element at the free end of the arm, a spring loop intermediate the ends of the arms, a helical spring terminally connected to one of said flanges and to said loop, a stop on the last-named flange, said spring normally holding the arm against said stop, means detachably connecting the spring with said loop to permit the spring to be slipped out of the loop when it is desired to move the arm from upright operative position to horizontal released position, and a latch on the last-named flange adapted to engage over the arm and hold it in released position.

2. The structure as in claim 1 and in which said spring connecting means comprises an eye on the spring engaged in said loop and adapted to be slipped down upon the rod below the loop.

3. The structure as in claim 1 and in which said stop consists of a flange projecting laterally from one of said upstanding flanges.

CLARENCE L. MULDER.
